UNITED STATES PATENT OFFICE.

JEREMIAH MORROW, OF WELLSTON, OHIO.

LOADING APPARATUS.

Application filed July 12, 1922. Serial No. 574,515.

To all whom it may concern:

Be it known that I, JEREMIAH MORROW, a citizen of the United States, residing at Wellston, in the county of Jackson and State of Ohio, have invented a new and useful Loading Apparatus, of which the following is a specification.

This invention relates to loading apparatus and is designed primarily for loading 10 coal from the floor of a mine onto cars lined up adjacent the apparatus. It has been the practice generally to employ men for shoveling the coal into the cars. Some machines have been devised for gathering the coal 15 and directing it into wagons or cars but as a general rule this machinery has been very bulky, extremely high priced, and has not operated with sufficient speed to justify its installation.

20 One of the objects of the present invention is to provide a loading apparatus which will be fed automatically along the floor of the chamber in the mine, moving continuously, if desired, from one end to the other 25 of the chamber and picking up the coal and discharging it laterally into cars positioned at one side of the path of movement of the apparatus.

Another object is to provide mechanism of 30 this character the elevating means of which scrape along the smooth floor of the mine so as to insure the proper picking up of the pieces of coal and their conveyance to the delivery mechanism.

35 Another object is to provide simple and efficient means whereby an operator moving with the apparatus can guide it readily so as to hold it to its proper course during the loading operation.

40 With the foregoing and other objects in view which will appear as the description proceeds, the invention resides in the combination and arrangement of parts and in the details of construction hereinafter described 45 and claimed, it being understood that, within the scope of what is claimed, changes in the precise embodiment of the invention shown can be made without departing from the spirit of the invention.

50 In the accompanying drawings the preferred form of the invention has been shown,

In said drawings—

Figure 1 is a top plan view of the loading apparatus.

55 Figure 2 is a bottom plan view thereof.

Figure 3 is a vertical longitudinal section.

Figure 4 is a transverse section taken longitudinally of the transverse conveyor.

Figure 5 is a longitudinal section through the drum of the back haul line and through 60 the parts adjacent thereto.

Fig. 6 is a detail view of a portion of the worm gearing.

Figure 7 is a longitudinal section through the adjustable line guiding carriage. 65

Figure 8 is a transverse section through a portion of the driving mechanism.

Figure 9 is a transverse section through 70 one of the worm conveyors and the adjacent portion of its trough.

Referring to the figures by characters of reference 1 designates the upstanding side plates of the frame of the apparatus, these being connected at their back ends by a transverse structure 2 and, at other points, 75 by cross strips or beams 3 serving to reinforce the structure. Axles 4 are journaled within the sides of the frame and are supported by wheels 5 whereby the apparatus can be moved readily over the floor of the 80 mine. Interposed between and secured to the sides of the frame is an inclined plate 6 having a straight front edge indicated at 7 while back from this edge the incline is so shaped as to provide longitudinally extending troughs 8. The rear or upper portion of the inclined plate is provided with a rearwardly and downwardly inclined flange 9 extending from one side to the other of the apparatus and overhanging one edge 90 of a transversely extending endless conveyor 10. An angularly adjustable frame 11 is extended laterally from the rear portion of one side of the frame of the apparatus and a shaft 12 is journaled in the free end of 95 this adjustable frame and carries sprockets 13. These sprockets engage the chains 14 of conveyor 10 and said chains also engage sprockets 15 mounted on a longitudinal shaft 16 journaled in the rear structure 2 of the 100 main frame and in a suitable bearing 17 extending from one of the beams 3. The upper flight of the belt is supported by cleats 18 so that it will not sag and similar cleats 19 are also extended inwardly from the 105 sides of the adjustable frame 11 so as to support that portion of the upper flight mounted within the frame. It will be noted that the chains of the belt are connected by cross rods 20 so as to provide a proper support for 110 the fabric of the belt. Cross ribs 21 are arranged on the outer or active face of the belt

for engagement with the material being handled.

Obviously any material delivered upwardly along the troughs 8 will be discharged over the flange 9 and onto the belt 10 which, in turn, will operate to convey the material laterally and thence upwardly so as to deliver it from the upper end of the frame 11.

10 Arranged within the forward portions of the troughs 8 are bearings 22 and additional bearings are extended upwardly from the flange 9 as shown at 23. In these bearings are journaled worm conveyors 24 supported 15 longitudinally within the troughs, one of these conveyors being provided in each trough and each conveyor being pitched oppositely to the next adjoining conveyor. This is clearly indicated in Figure 1. The 20 front ends of the worm conveyors are tapered and project beyond the edge 7 of the inclined plate 6, the points of these conveyors being adapted to scrape along the floor of the mine over which the wheels 5 are traveling.

Secured to the rear end portion of each of the worm conveyors is a gear 25, all of these gears being constantly exposed and the diameters of the gears being preferably equal 30 to or less than the greatest diameters of the worm conveyors. The gears mesh with a series of screws 26 carried by a transverse shaft 27 and secured to one end of this shaft is a gear 28 constantly in mesh with a larger 35 gear 29 loosely mounted on a transverse shaft 30 extending under the inclined plate 6. This gear has a clutch member 31 connected thereto so as to rotate therewith. Another clutch member 32 is feathered on the 40 shaft 30 and is adapted to be shifted by a hand lever 33 fulcrumed for example as at 34 and extending rearwardly from the main frame at a point where it can be conveniently grasped and actuated by the operator. 45 Obviously when the lever is in one position shaft 30 can rotate without actuating the gear 29 and the parts driven thereby whereas when the lever is in another position gear 29 will be coupled to the shaft. Shaft 16 50 has a gear 16' which meshes with one of the worms 26 on shaft 27.

Shaft 30 is adapted to be driven by means of a gear 35 secured thereto and receiving motion from a gear 36 secured to the shaft 55 36'. This last named shaft constitutes the main drive shaft of the mechanism and is adapted to be driven by a suitable motor 37 carried by the main frame and which can transmit motion to the shaft through gears 60 such as indicated at 42.

A gear 41 is secured to shaft 30 so as to rotate therewith and this gear constantly meshes with a gear 42 mounted to rotate freely on a transverse shaft 43. Gear 40 has 65 a clutch face 44 on each side thereof and

feathered on the shaft is a clutch member 45 adapted to move with a frame 46 which bridges gear 42 and slides along the shaft 43. Another clutch member 47 is engaged by and moves with the frame 46 but is mounted to rotate freely on the shaft 43 and this clutch member 47 has a drum 48 rotatable therewith. A shifting lever 49 is suitably mounted, as at 50, beneath the inclined plate 6 and is connected at 75 one end to the frame 46 while its rear end can be readily grasped and moved by the operator located at the back of the machine. By shifting frame 46 in one direction gear 42 will be coupled to the shaft 43 and thus 80 cause the shaft 43 to rotate independently of the drum 48. By shifting the frame 46 in the other direction, however, the shaft 43 will be uncoupled from the gear 42 while drum 48 will be coupled to said gear and 85 will be rotated thereby upon the shaft 43.

Secured to the projecting ends of the shaft 43 are drums 51 and secured to and wound upon these drums are out-haul cables 52 which extend upwardly over guide sheaves 90 53 supported above the sides 1 of the frame and then converge forwardly so as to pass between a pair of sheaves 54 mounted in a carriage 55. This carriage is mounted on a transversely extending screw 56 journaled 95 in standards 57 on the side 1 near the front of the apparatus. A guide loop 58 is extended upwardly from the front portion of the carriage 55 and the out-haul cables 52 are extended therethrough and forwardly 100 to any suitable point where they can be securely fastened.

A sprocket 59 is secured to one end of the screw 56 and is engaged by a chain 60 extending rearwardly to a sprocket 61. This 105 sprocket is adapted to be rotated by the operator so as thus to rotate the screw 56 and shift the carriage 55 toward one side or the other of the apparatus.

After a quantity of coal has been deposited on the floor of the chamber in the mine, the apparatus constituting the present invention is set at one end of the chamber and the cables 52 are extended forwardly and secured to a rigid structure at some point 115 in the path of movement of the apparatus. A back-haul cable 62 is wound about and secured to the drum 48 and is secured to a fixed structure in rear of the path of movement of the apparatus. A track for supporting cars 120 to be loaded is arranged alongside the path of the apparatus so that the laterally discharging belt 10 will elevate material above and deliver it downwardly into one of the cars.

After the apparatus has been properly arranged the motor 37 is set in operation and will thus drive shafts 36' and 30. By shifting lever 33 the shaft 27 can be coupled or geared to shaft 30 so that all of the 125 130

worm or spiral conveyors 24 will be rotated simultaneously. Each worm will rotate oppositely to the adjoining worm and all of them will cooperate to direct engaged material upwardly within the troughs 8 and onto the belt 10. The belt 10 is of course driven by the shaft 16. By shifting clutch member 45 into engagement with one of the clutch members 44 the drums 51 will be rotated and the out-haul cables 52 will be wound thereon. Accordingly the apparatus will be drawn forward gradually and the points of the spiral or worm conveyors 24 will slide along the floor of the mine and plow under the pile of coal. At the same time these conveyors will move the coal rearwardly within the troughs and direct it onto the belt 10. By shifting carriage 55 during this movement the line of draft can be varied, thus to slightly change the direction of movement of the apparatus and properly guide it during the operation.

Should it be desired to reverse the movement of the apparatus it is merely necessary to shift lever 49 so as to engage clutch member 47 with clutch member 44 and uncouple gear 42 from shaft 43. This will result in the actuation of drum 48 and the winding of the back-haul line 62.

30 With an apparatus of the class described a path several feet in width can be cleared of coal and the material conveyed rearwardly and upwardly and thence laterally so as to be directed into the cars provided therefor. Importance is attached to the fact that empty cars can be arranged along the side of the path of the apparatus where they can be brought conveniently into position to receive the delivered material.

40 While the apparatus has been designed primarily for loading coal in mines it is to be understood that it can be used for loading other material such as stones, etc.

Attention is called to the fact that the carriage 55 is located at a higher level than the drum 51. Thus it will be apparent that when the out-haul lines are under tension during the forward movement of the apparatus they will exert downward pressures on the carriage and likewise upon the front portion of the apparatus, thus to maintain the front edge 7 of the inclined plate and the front ends of the spiral conveyors in intimate contact with the surface on which the apparatus is mounted.

What is claimed is:-

1. Loading apparatus including a movably supported inclined plate, a series of spiral conveyors thereabove and having 60 tapered ends projecting forwardly beyond the inclined plate, a carriage movably sup-

ported above the conveyor, winding drums at the sides of the inclined plate, out-haul cables extending through the carriage and connected to the drums, means for simultaneously rotating the drums and the conveyors to feed the apparatus forwardly and elevate engaged material, and means for shifting the carriage to guide the apparatus. 65

2. Loading apparatus including an inclined plate movably supported, spiral conveyors above and projecting forwardly beyond the inclined plate, a carriage movably mounted above the conveyors, out-haul cables extending through the carriage, 70 means for simultaneously taking up said cables and rotating the spiral conveyors, and means for adjusting the carriage laterally relative to the inclined plate to guide the apparatus. 75

3. Loading apparatus including a movably supported inclined plate, spiral conveyors thereabove and projecting forwardly therebeyond, a transversely extending adjusting screw supported above the inclined plate, a carriage engaged thereby, out-haul cables extending through the carriage, means remote from the carriage for actuating the screw to shift the carriage laterally, and means for taking up the out-haul lines 80 to propel the apparatus. 85

4. Loading apparatus including a movably supported inclined plate, spiral conveyors above and projecting forwardly beyond the inclined plate, a laterally adjustable carriage supported above the forward portion of the inclined plate, winding drums, out-haul lines engaging the carriage and extending to the drums, said drums being located at a lower level than the carriage, and means for rotating the drums to propel the apparatus forwardly and to set up a downward pressure upon the carriage and the front portion of the apparatus from the out-haul lines. 100

5. Loading apparatus including a movably supported inclined plate, spiral conveyors above and projecting forwardly from the inclined plate, a laterally adjustable carriage above the forward portion of the inclined plate, out-haul lines engaging the carriage, drums connected to the out-haul lines, a back-haul line, a drum engaged thereby, driving mechanism carried by the apparatus, and means for transmitting motion from said mechanism to the drums of the out-haul lines or to the drum of the back-haul lines. 110

In testimony that I claim the foregoing as my own, I have hereto affixed my signature. 120

JEREMIAH MORROW.
